UNITED STATES PATENT OFFICE

DANIEL J. BELLIN, OF BRONX, NEW YORK, N. Y.

COLLAPSIBLE CONTAINER

Application filed October 25, 1927. Serial No. 228,546.

This invention relates to collapsible containers.

One of the objects of this invention is the provision of an improved container which can be "knocked down" to permit packing and shipping in compact form, and which can be rapidly set up for use into a practically rigid, self-sustaining position.

A further object of this invention is to provide a container of the character set forth, having an improved corner construction providing for interlocking the walls of the container in a particularly neat and efficient manner when in set up position, and serving also as a reenforcement for said walls, while at the same time permitting assembly of the box with maximum celerity and convenience.

A further object of this invention is to provide a unitary blank for a container of the character set forth, of such design and construction as to make for a high degree of economy in labor and material in setting up the completed container therefrom.

Other objects of this invention will in part be obvious and in part hereinafter pointed out.

The invention accordingly consists in the features of construction, combinations of elements, and arrangement of parts which will be exemplified in the construction hereinafter described, and of which the scope of application will be indicated in the following claims.

In the accompanying drawing, in which is shown one of the various possible illustrative embodiments of this invention,

Fig. 1 is a plan view of a blank embodying the invention, indicating scored bend lines and cut-outs for a purpose hereinafter to appear.

Fig. 2 is a fragmentary plan view of a corner of a container member in set up position.

Fig. 3 is a fragmentary perspective view of said corner.

Fig. 4 is a perspective view of a container member made according to the invention.

Fig. 5 is a fragmentary perspective view of the blank for said container member, knocked down for shipment and ready to be

folded to form the container of the invention.

Referring in detail to the drawings, B denotes a blank embodying the invention. Said blank is made of any suitable material, preferably a fibrous material, such as compressed paper board having the desired stiffness, and cut into a single piece, here shown as of rectangular form. Said blank may be provided with the longitudinal fold lines 10, and the transverse fold lines 12 which may be scored upon blank B. These several lines define a body portion 13, and end and side sections 14 and 16, and the corner sections 18. Fold lines 10 and 12 intersect at points 20, from which points fold lines 22 extend diagonally to the corners of blank B, dividing corner sections 18 into the triangular sections 24, 26. A slit line 28 defines a tongue 30 cut in each section 24, the neck 32 of the tongue being on the portion 34 of the fold line 10 bounding corner section 18. A slit 36 is cut at a side of each triangular section 26 along the portion 33 of fold line 12 which forms a boundary for corner section 18.

In preparing the blank B for shipment to the point of use, or in preparing it for storage, it is desirable to set it up in such manner that the finished container may be swiftly developed from this intermediately prepared product. For these purposes, the blank B is folded inwardly on the lines 10, so that the corner sections 18 will lie on top of the end sections 14 while the side sections 16 will be superimposed along the sides of and upon the body portion 13. Rivets 40 may now be driven through each end section 14 to secure thereto the superimposed triangular section 24, the rivets being applied so as to engage that portion of the triangular section 24, not bounded by the slit line 28 and portion 34 of fold line 10. By this construction, there is provided an intermediate form F which lends itself readily to shipment because of its inherent adaptability for assembly, hereinafter appearing.

When it is desired to set up a container C for use, a folded form F is used in the following manner. The end sections 14 and their secured triangular sections 24 are bent upwardly and inwardly of body portion 13.

Simultaneously side sections 16 will rise upwardly and bend outwardly from body portion 13, and triangular section 26 will be folded on line 22 into abutment with the face 5 of section 24, with slit 36 appearing in position to receive the tongue 30 which has been sprung from triangular section 24 before the last bending operations were begun.

Said tongue, as apparent from the drawing, 10 has a peculiar configuration for the purpose of facilitating the formation of container C and thereafter retaining the several parts thereof in fixed relation, and for resisting any undue strains that may be brought to 15 bear upon said container. Tongue 30 is seen to terminate in the tapered end portion 42, which extends from a reduced body portion 44, the greatest width of which is less than the length of slit 36. The edges 46 of the 20 tongue 30 at said body portion have the appearance of troughs. This effect is produced by a decided increase in the width of tongue 30 as the edges 46 approach the neck of said tongue. Adjacent the neck of said 25 tongue is a bulge 48 of slightly greater width than the length of said slit, while at the neck, the tongue is reduced so as to be snugly received in said slit.

It can, therefore, be seen that, during the 30 simultaneous operation of bending sections 14, 16, 24 and 26 into their respective positions, the tapered end portion 42 may be inserted into slit 36 at each corner of container C, reduced body portion 44 smoothly entering 35 said slit until bulge 48 engages therewith. A slightly increased pressure on the outer face of end section 14 adjacent tongue 30 will serve to force bulge 48 through slit 36 and allow secure engagement between the 40 reduced neck portion 32 of the tongue and said slit. It will be understood that a closed container may now be assembled, either by covering container C by a similar section, or by any other section of similar or different 45 construction. In the drawing, however, for purposes of clarity, the cover section has been omitted.

By the herein described construction of 50 container C, a reinforced corner construction for said container is provided without the use of any material other than that embodied in the single blank from which the container proper is formed. Furthermore, a container, 55 readily set up from or collapsed into small convenient compass for shipping and like purposes, is produced.

It will thus be seen that there is provided 60 a device in which the several objects of this invention are achieved, and which is well adapted to meet the conditions of practical use.

As various possible embodiments might be 65 made of the above invention, and as various changes might be made in the embodiment above set forth, it is to be understood that

all matter herein set forth or shown in the accompanying drawing is to be interpreted as illustrative and not in a limiting sense.

Having thus described my invention, I claim as new and desire to secure by Letters Patent:

1. A container having end and side walls connected by integral corner portions, each corner portion being folded diagonally and lying inside of the box and adjacent one of said walls, a single slit being formed at an edge of the corner portion, and a tongue cut from said corner portion and folded from another edge of said corner portion to engage in said slit. 75

2. A container having end and side walls connected by corner portions, each corner portion being folded diagonally and lying against a wall of the box, a slit being formed at an edge of the corner portion, and a tongue cut so as to be folded from another edge of said corner portion to engage in said slit. 80

3. A container having end and side walls connected by corner portions, each corner portion being folded diagonally and lying inside of the box, a slit being formed at an edge of said corner portion, a tongue cut out from said corner portion and folded on another edge of said portion to engage in said slit, and a permanent fastening means in proximity to said cut-out, securing one section only of said corner portion to the adjacent wall of the box. 90

4. A folding container having end and side 100 walls connected by corner portions, each corner portion being diagonally folded and lying inside of the box, said corner portion having a tongue foldable at one edge thereof and a slit in another edge thereof, said tongue 105 being engaged in said slit to hold adjacent side walls of said container together, and permanent fastening means in proximity to said tongue for securing one folded section only of said corner portion to an adjacent 110 wall of the box. 110

5. A substantially rectangular one piece blank for making a container of the character described having fold lines marked thereon extending longitudinally and transversely of said blank, said lines defining a body, side and end walls for said container and integral corner portions, diagonal lines extending from the intersections of said longitudinal and transverse lines across said corner portion to adjacent corners of said blank, and forming triangular sections, a tongue 115 form slotted in one of said sections, and a single slit formed along a fold line between the other sections and an adjacent wall of the 120 container. 125

In testimony whereof I affix my signature.
DANIEL J. BELLIN.
